UNITED STATES PATENT OFFICE.

STEPHEN BOURNE, OF NEW YORK, N. Y., ASSIGNOR TO C. BRANDES, INC., OF NEW YORK, N. Y., A CORPORATION OF NEW YORK.

DESIGN FOR A LOUD SPEAKER FOR RADIO REPRODUCTION.

Application filed November 26, 1924. Serial No. 11,487. Term of patent 14 years.

To all whom it may concern:

Be it known that I, STEPHEN BOURNE, a citizen of the United States, residing at 30 West 59th Street, New York city, in the county of New York and State of New York, have invented a new, original, and ornamental Design for a Loud Speaker for Radio

Reproduction, of which the following is a specification, reference being had to the accompanying drawings, forming part thereof.

Figure 1 of the drawings shows a front view of my loud speaker for radio reproduction; Fig. 2 is a side view of the loud speaker; Fig. 3 is a top plan view of the loud speaker showing my new design.

I claim:

The ornamental design for a loud speaker for radio reproduction.

STEPHEN BOURNE.
